INNERSOLE HAVING UPWARDLY FOLDABLE PORTIONS

Samuel Pennell, Brooklyn, N. Y.

Application December 18, 1947, Serial No. 792,513

2 Claims. (Cl. 36—43)

1 This invention relates to innersoles treated with medications in such manner as to provide uniform distribution thereof throughout the innersole. Still more particularly, the invention deals with the formation of an innersole blank which is so constructed that, in the use of an innersole in a shoe, the innersole will automatically shift to comfortably conform to the foot, supply to the foot medication, which will produce and maintain a substantially sterile condition in a predetermined use of the innersole in the shoe.

The novel features of the invention will be best understood from the following description, when taken together with the accompanying drawing, in which certain embodiments of the invention are disclosed and in which the separate parts are designated by suitable reference characters in each of the views and in which:

Fig. 1 is a plan view of a blank innersole, indicating in dotted lines diagrammatically the general outline of the innersole when in use.

Fig. 2 is a side view of a blank, indicating its arrangement in a shoe, the latter being shown in dotted lines and in dot-dash lines is shown the side edge contour of the inner-sole as appearing after a predetermined use thereof in the shoe.

Fig. 3 is a side edge view of the innersole in the form acquired thereby in said predetermined use.

Fig. 4 is a rear view of the heel portion of the innersole as seen in Fig. 3; and

Fig. 5 is a section on the line 5—5 of Fig. 3.

It is the purpose of my invention to provide a paper innersole, wherein the paper employed is of a texture or characteristic having highly moisture absorbent properties and, further, wherein the paper is treated with medications so as to produce and maintain in the use of the innersole in the shoe a substantially sterile condition, particularly in eliminating the development of soreness or irritation due to the presence of excess moisture or sweating and also to eliminate common foot ailments, such as athlete's foot, ringworm, and the like.

It is preferred that the production of the paper is on the basis to produce what might be termed a neutral paper which is not excessive in acid or alkaline phases. I have found that sodium bicarbonate can be utilized as a medication to act in neutralizing excessive acid conditions which may prevail. Further, talcum is employed to present a smooth wearing surface and also in providing what might be termed a dry lubricant. Undecylenic acid, in minute amounts employed on the innersole, will prevent formation of

2 fungous growths and, when larger concentrations are employed, they will act to destroy a fungous growth.

It is further the purpose of my invention to provide innersoles which can be inexpensively produced, thereby facilitating a minimum length of use, for example, a one day use, after which the innersoles are disposed of and new innersoles used the following day. People who are on their feet a great deal or do considerable walking through the day are subjected to the formation of foot soreness, irritations and other foot ailments of the type indicated and, by using innersoles of the type and kind herein disclosed, these difficulties and objectionable characteristics can be overcome and the feet maintained in a healthy, sanitary or substantially sterile condition at all times. The innersole also provides a slight cushion within the shoe for ease and comfort to the wearer.

In Fig. 1 of the drawing, I have shown an innersole blank at 10, formed from paper of the kind heretofore described and die-cut or blanked to form a toe portion 11, instep 12 and heel portion 13. The sides of the instep and heel portion are made slightly wider than the normal width of the shoe interior, as is indicated at 12', 13', and these extensions also will prevail in some instances at the toe portion, as indicated at 11' in Fig. 3 of the drawing.

Considering Fig. 1 of the drawing, it will also appear that the rear portion of the heel 13 has other extensions, as at 14 and 15, the latter being formed by notched or cutout portions at the sides of the innersole, as seen at 16 and 17, and centrally of the rear edge of the innersole, as seen at 18. These notches allow the parts 14 and 15 to extend upwardly in the manner shown in Figs. 3 and 4 and also indicated in Fig. 2, as the inner-sole automatically compensates itself to fit within the shoe, as later described, and also allows the side extensions 13' to fold upwardly at the sides of the heel.

In the several views, particularly Figs. 3—5 inclusive, an attempt has been made to illustrate the final formation of the innersole as it is shaped in the use thereof in the shoe and as it would appear upon removal from the shoe, after a predetermined use thereof. The innersole will shape itself fairly well to the contour of the foot and thus have the rounded shapes which are at least diagrammatically shown in the drawing.

In the use of the innersole, the same, in its blank form as shown in Fig. 1, is placed in the shoe, as indicated by the side edge view thereof

shown in full lines in Fig. 2. In this position, the innersole would be substantially flat except for a slight curvature at the side edges of the shoe, which curvature is not attempted to be shown in Fig. 2 as it would add confusion. The innersole of a size is made to fit snugly in the shoe and conforms with the shoe interior except for the side extensions as at 11', 12' and 13'. Now then, when the shoe is worn, the operation of walking will cause the foot to automatically force the innersole backwardly in the direction of the heel, causing the extensions or flaps 14 and 15 to raise up at the back of the heel and the extensions 13', 12' and 11' to fold at the sides of the foot and a result substantially similar to that shown in Fig. 3 will be produced. Of course, with different feet and shoes, this contour will vary, primarily due to the fact that the innersole shapes itself, partly to the shoe and, also, to the foot. After the extensions, or flaps 14, 15 rise at the back of the heel and substantially come together at the notch 18 and the extensions 13' substantially meet the extensions 14, 15 at the notches 16, 17, the innersole then maintains this position throughout the continued use thereof during the day.

The advantage of constructing an innersole in the manner above described makes it possible for each innersole to automatically compensate and fit properly upon the foot.

It will be understood that a single blank suitable for forming all the innersoles, as for example, paper, is medicated throughout its entire body, so that medication prevails on both surfaces of the innersole. This is distinctly advantageous, as it minimizes the number of die formations in producing innersoles of different sizes.

By reason of the economical cost of production, the innersoles may be packaged in bulk, suitable to provide weekly or monthly supplies to the user at a relatively nominal cost.

The cuts or V-notches formed in the rear edge and rear side edges of the innersole produces what may be termed relatively moving and flexing portions which, when moved into the raised position, encircle the foot. The side edges of the innersole forwardly of the heel portion also flex or bend upwardly in conforming to the shoe and foot and thus extending the cushioning throughout substantially the entire area of the shoe except for the extreme toe portion where the innersole has moved backwardly to compensate for the rise or upward extension of the heel as the innersole automatically moulds itself to the foot. The innersole, while fitting the shoe and conforming to the shoe insofar as length is concerned, is oversize as to width thus facilitating extensions

of the sides of the inner sole around the side edge portions of the foot particularly at the heel.

Having fully described my invention what I claim as new and desire to secure by Letters Patent is:

- 5 1. An innersole for shoes, comprising a unitary sheet of thin highly flexible material conforming generally to the contour of the interior of a shoe bottom and oversize as to the heel and instep interior of said shoe bottom, the heel portion of the innersole having notches on opposed sides and centrally of the rear edge thereof extending from the outer periphery of the heel portion through the edge of the innersole proper, the corners of 10 said notches terminating at said edges in rounded enlargements, said notches forming on the rear edge of the heel portion separate relatively flexing members, and said members, in the use of the innersole, being adapted to form, within the heel portion of a shoe, raised walls abutting centrally of the heel portion of the shoe.

- 15 2. An innersole for shoes, comprising a unitary sheet of thin highly flexible material conforming generally to the contour of the interior of a shoe bottom and oversize as to the heel and instep interior of said shoe bottom, the heel portion of the innersole having notches on opposed sides and centrally of the rear edge thereof extending from the outer periphery of the heel portion through the edge of the innersole proper, the corners of 20 said notches terminating at said edges in rounded enlargements, said notches forming on the rear edge of the heel portion separate relatively flexing members, and said members, in the use of the innersole, being adapted to form, within the heel portion of a shoe, raised walls abutting centrally of the heel portion of the shoe and having edges abutting edges of said members.

SAMUEL PENNELL.
